FIG. 12

FIG. 13

FIG. 14

FIG. 15

FIG. 16

FIG. 1 is a perspective view of a table showing my design;

FIG. 2 is a plan view;

FIG. 3 is a view in side elevation taken from the left in FIG. 1;

FIG. 4 is a view in end elevation;

FIG. 5 is a perspective view of a modified form of the table of FIG. 1;

FIG. 6 is a plan view;

FIG. 7 is a view in side elevation;

FIG. 8 is a view in end elevation taken from the right in FIG. 5;

FIG. 9 is a perspective view of the table of FIG. 1 illustrating the appearance thereof wherein the top is opaque and the base is transparent;

FIG. 10 is a plan view;

FIG. 11 is a view in side elevation;

FIG. 12 is a view in end elevation;

FIG. 13 is a perspective view of the table of FIG. 5 illustrating the appearance thereof wherein the top is opaque and the base is transparent;

FIG. 14 is a plan view;

FIG. 15 is a view in side elevation; and

FIG. 16 is a view in end elevation.

This application is a continuation of application Ser. No. D. 22,539, filed Apr. 20, 1970, which is a continuation of my applications Ser. Nos. D. 18,146, D. 18,147, D. 18,148, and D. 18,149, filed June 18, 1969.

I claim:

The ornamental design for a table or the like, as shown and described.
